CLAIM

USPC **D14/492**

The ornamental design for a display screen portion with icon for sphygmomanometer, as shown and described.

(58) **Field of Classification Search**

DESCRIPTION

USPC D14/485-495

FIG. 1 is a front view of a first embodiment of a display screen portion with icon for sphygmomanometer showing my new design.

CPC G06F 3/048; G06F 3/0481; G06F 3/0482; G06F 3/04817; G06F 3/0482; G06F 3/0483; G06F 3/0484; G06F 3/04847; G06F 3/0485; G06F 3/04855; G06F 3/04886; G06Q 30/00; H03J 1/00; H03J 1/0008; H03J 1/0016; H03J 1/0025; H04N 5/00; H04N 5/08; H04N 5/14; H04N 5/222; H04N 5/225; H04N 5/232; H04N 5/445; H04N 5/44543; H04N 5/45; H04N 2005/44517; H04N 2005/44521; H04N 2005/44526; H04N 2005/4453; H04N 2005/44534; H04N 2005/44539; H04N 2005/44547; H04N 2005/44556; H04N 2005/4456; H04N 2005/44565; H04N 2005/44569; H04N 2005/44573;

FIG. 2 is a front view of a second embodiment of a display screen portion with icon for sphygmomanometer showing my new design; and,

FIG. 3 is a front view of a third embodiment of a display screen portion with icon for sphygmomanometer showing my new design.

The broken lines illustrate a portion of the display screen and form no part of the claimed design. The solid black shading depicts a color contrast.
